UNITED STATES PATENT OFFICE.

JULES COURTIER, OF PARIS, FRANCE.

RESTORER OF NORMAL IGNITION FOR DUAL-IGNITION APPARATUS OF INTERNAL-COMBUSTION ENGINES.

Original application filed July 31, 1923, Serial No. 654,879. Divided and this application filed December 11, 1923. Serial No. 680,009.

To all whom it may concern:

Be it known that I, JULES COURTIER, citizen of the Republic of France, of 20 Rue Ernest Cresson, Paris, France, have invented 5
a Restorer of Normal Ignition for Dual-Ignition Apparatus of Internal-Combustion Engines, of which the following is a full, clear and exact description.

This invention relates to an auxiliary apparatus for internal combustion engines having dual ignition for producing regulable break sparks for doing away with misfires due to the sooting of sparking plugs and automatically cleaning these plugs during 15 the running of the engines and of the vehicles driven by them.

This invention covers an improvement over applicant's copending application 654879 1/2 filed July 31, 1923 in that it permits of normal ignition in a circuit fed by one source, while at the same time permitting the introduction of a series of a variable number of breaking sparks in another circuit fed by another current source. The present 25 improvement also has a circle divided into two conductive segments and two series of separate contacts, said circle being controlled by the operating handle passing under the pairs of fixed contacts. Moreover this arrangement is independent of the magneto which latter is combined with the earlier construction.

This apparatus permits a single controlling organ to effect the introduction of 35 break sparks regulable at will, separately into one or the other of two ignition circuits.

The general arrangement is such that when the apparatus is at rest the two ignitions work without any secondary spark 40 gap, and when one of the ignitions is working with break sparks the other ignition continues to work without break sparks.

The invention is clearly illustrated in the accompanying drawings, in which:—

45 Figure 1 is a vertical sectional view of an arrangement of apparatus comprising for each ignition a conducting armature composed of two parts, the one continuous and the other divided by gaps into multiple contacts, and, Figure 2 is a fragmental sectional detail of a slightly modified arrangement of the apparatus.

The apparatus shown comprises an insulating support 2' in the form of a disc rota-

55 tably mounted in a casing 6'. This insulating disc is provided with a handle 26' which permits it to be turned about its pivotal axis 25'.

Upon this disc 2' there are rigidly fixed 60 two semi-circular conducting armatures A'¹, A'², one on each side of a diameter. Each of the conducting armatures A'¹, A'², comprises a continuous segment 30, 31, and a segment cut by the gaps 32, 32', 32'', etc. . . ., and 33, 33', 33'', etc. . . ., dividing it 65 into a plurality of contacts 34, 34', 34'', etc. . . ., and 35, 35', 35'', etc. . . .

70 Non-conducting partitions 36, 36', electrically insulate the armatures A'¹, A'², from each other.

Upon the casing 6' are rigidly fixed the terminals 17 and 5, and 17' and 5', for connecting the apparatus within the double ignition circuits.

These terminals are directly connected 75 with nuts which secure the metal springs 37, 38, and 39, 40, terminated by brushes 41, 42, and 43, 44, which remain in contact with the armatures A'¹ and A'², both when the apparatus is in its normal position of rest and 80 also when it is brought into operation, to introduce secondary spark gaps.

85 In engines with fixed cylinders, the apparatus described is inserted so that it is arranged, as far as concerns the electrical connections, between the collector and the distributor of the magneto of the first ignition circuit through its terminals 5 and 17, and between the collector and the distributor 90 of the magneto of the second ignition circuit through its terminals 5' and 17'. As concerns the electrical connections to rotary engines, the apparatus is inserted between the collector of the magneto and the distributor of the cylinders of the first and 95 of the second ignition circuits respectively through the same terminals 5, 17 and 5', 17'.

The operation of the device is as follows:

Suppose the electric current of the ignition M¹ enters the apparatus by the flexible 100 wire 45 and leaves it by the flexible wire 46, and the ignition current M² enters the apparatus by the flexible wire 47 and leaves it by the flexible wire 48.

105 When the apparatus is at rest the circuit of the ignition M¹ is closed by the continuous blade 30 between the two brushes 41 and 42, and the current of the ignition M²

is closed by the continuous blade 31 between the two brushes 43 and 44.

For restoring the ignition of the fouled sparking plugs and for cleaning the same, if the misfires are produced in the ignition circuit M^1 , the handle 26' is moved in the direction of the arrow a' . The brush 41 leaves the continuous segment 30 of the armature A'^1 in order to pass successively over the associated fractional contacts 34, 34', 34'', etc. . . of this armature. The gaps 32, 32', 32'', etc. . . are introduced in this manner into the ignition circuit M^1 , thereby producing break sparks conjugated in series in this circuit.

During this time the armature A'^2 turns also in the direction of the arrow a' . The brushes 43, 44, do not leave the continuous blade 31, but slide upon it and the ignition circuit M^2 remains closed without any secondary spark gaps.

When the number of break sparks in series introduced into the ignition circuit M^1 is sufficient to reestablish the normal spark-
ing at the points of the fouled sparking plug and the misfires are no longer heard, the handle 26' is secured in the place to which it has been moved, this handle being provided upon its lower face with a stud 28' adapted to engage in one of the notches 27' with which the casing 6' is provided.

At the end of the time necessary for cleaning the sparking plug the handle 26' is returned to the medium position in which the apparatus is at rest and the two ignition circuits operate again without break sparks.

If the misfires are taking place in the ignition M^2 , the disc support 2' is turned in the direction of the arrow b' . The brush 43 leaves the continuous blade 31 of the armature A'^2 and passes successively upon the contacts 35, 35', 35''. Sparks electrically arranged in series are produced in the associated gaps 33, 33', 33'', etc. . . in the ignition circuit M^2 .

During this movement the ignition circuit M^1 remains closed without secondary spark gap for the brushes 41 and 42 while sliding remain in contact with the continuous blade of the armature A'^1 .

In another constructional form of the ap-

paratus, the brushes 41 and 43, when leaving respectively, through the motion of the disc 2', the contact on to the continuous blades 30 and 31, instead of sliding in contact onto separated contacts 34, 34', 34'', etc. . . and 35, 35', 35'', etc. . . , are kept at a short distance from the said contacts, the curve of said contacts being of a smaller radius than that of the continuous blades. Thereby a break spark jumps between 41 and the contacts 34, 34', 34'' or between 43 and 35, 35', 35'', the break sparks in series continuing to jump in the gaps 32, 32', 32'', etc. . . or 33, 33', 33'', etc. . .

The arrangements above described are given by way of example only; the forms, dimensions, materials employed and all detail may be varied without changing the principle of the invention.

Claims.—

1. An auxiliary apparatus for internal combustion engines having dual ignition, comprising two pairs of conducting organs inserted one in the first and the other in the second high tension ignition circuit; each pair of conducting organs consisting of a continuous blade and a blade divided into a series of contacts separated by gaps; the two sets of contacts being mounted on an insulating support, a control organ to operate this support; fixed brushes bearing on each set of contacts.

2. An auxiliary apparatus for internal combustion engines having dual ignition comprising two pairs of conducting organs inserted one in the first and the other in the second high tension ignition circuit; a continuous conducting segment and a conducting segment divided in a series of contacts separated by spark gaps inserted in each of the two circuits; the two pairs of segments being mounted on an insulating disc; a handle to operate the disc; fixed brushes bearing on each pair of segments.

The foregoing specification of my "Restorer of normal ignition for dual ignition apparatus of internal combustion engines" signed by me this 30th day of November 1923.

JULES COURTIER.
